US0D1102548S

(12) **United States Design Patent** (10) **Patent No.:** **US D1,102,548 S**
(45) **Date of Patent:** **** Nov. 18, 2025**

(54) **FILTER CARTRIDGE**

- (71) Applicant: **Brita LP**, Oakland, CA (US)
(72) Inventors: **Elizabeth Bransford**, Pleasanton, CA (US); **Russell E. Bell**, Pleasanton, CA (US); **David Zhong**, Pleasanton, CA (US); **Jonathan McDonald**, Snohomish, WA (US)
(73) Assignee: **BRITA LP**, Brampton (CA)
(**) Term: **15 Years**
(21) Appl. No.: **29/979,706**
(22) Filed: **Dec. 19, 2024**

Related U.S. Application Data

- (62) Division of application No. 29/889,921, filed on Apr. 18, 2023, now Pat. No. Des. 1,059,541.

(57) **CLAIM**

The ornamental design for a filter cartridge as shown and described.

DESCRIPTION

FIG. 1 is a top front isometric view of a filter cartridge showing the claimed design;

FIG. 2 is a bottom rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dashed broken lines in the figures show portions of the filter cartridge that form no part of the claimed design.

The dot-dash broken lines in the figures show boundaries that form no part of the claimed design.

1 Claim, 8 Drawing Sheets
